TITLE SUPPORTING STRIP

Thomas D. Corcoran and Merrill W. Hard,
Los Angeles, Calif.

Application November 19, 1934, Serial No. 753,676

11 Claims. (Cl. 108—10)

This invention relates to a device for fastening roofing tile in place on a roof structure, and more particularly pertains to improvements in tile supporting hangers of the type disclosed in a co-pending application for United States Letters Patent filed February 26, 1934, Serial Number 712,923.

An object of the invention is to provide a tile hanger adapted to serve as a connection between an anchor engaging a roof structure and wire ties engaging roofing tile to form supports for the tile, in which the hangers are so formed as to be adapted to be fastened at intervals throughout the water shedding surface of a roof in such fashion as to prevent or minimize leakage.

Another object of the invention is to provide a roofing tile hanger which is especially applicable for use on membrane covered roof structures where it is desirable or necessary to effect fastening of the hanger to the roof structure by nailing thereto through the water shedding membrane.

A further object is to provide a construction in the hanger whereby when the latter is applied to a roofing membrane by nailing the puncture formed in the membrane by the nail passing therethrough will be thoroughly sealed against possibility of leakage, and in which the hanger is so formed that when subjected to strains imposed thereon by the load of the tile suspended therefrom a portion of the hanger will be caused to be maintained disposed against the membrane above the point of penetration of the nail in such manner as to afford a tight seal.

Another object is to provide a hanger of the above character which is adapted to be employed in conjunction with tile supporting strips of the type formed with a series of longitudinally spaced extruded loops in effecting connection between a roof surface and an intermediate portion of the strip.

Various additional objects and features of the invention will appear and will be more fully understood from the following detailed description of a present preferred embodiment thereof, reference for this purpose being had to the accompanying drawing, in which:

Fig. 1 is a view of the hanger as seen in elevation;

Fig. 2 is a view in longitudinal section taken on the line 2—2 of Fig. 1;

Fig. 3 is a transverse section taken on the line 3—3 of Fig. 1;

Fig. 4 is a transverse section taken on the line 4—4 of Fig. 1;

Fig. 5 is a plan view illustrating the application of the invention;

Fig. 6 is a detail in longitudinal section of a hanger showing it as applied;

Fig. 7 is a detail in perspective illustrating the manner of employing the hanger in connection with a tile supporting strip;

Fig. 8 is a detail in perspective illustrating the manner of applying the hanger to a concrete roof;

Fig. 9 is a detail in perspective illustrating a modified form of the invention and depicting it as applied.

Referring to the drawing more specifically, A indicates generally the tile hanger which is here shown as embodying a plate 8 of sheet metal formed adjacent one end thereof with an extruded loop 9 which projects from the upper or outer face of the plate and extends longitudinally thereof. The plate is formed adjacent its other end with a semi-spherical protrusion 10 projecting from the upper or outer face of the plate to form a recess 11 on the back or under side thereof, as shown in Figs. 1 to 8, inclusive.

In forming the loop 9 the plate A is subjected to the action of a punch and die mechanism whereby a pair of parallel slits 12 and 13 of corresponding lengths are formed longitudinally of the plate and the material of the plate between the pair of slits is pressed outwardly to form a loop. In order to strengthen the extruded loop thus formed the material thereof is formed of arcuate cross section as particularly shown in Fig. 4 with the upper side or face of the loop concave and with its under side convex. The loop is also arched longitudinally and thus has imparted thereto a double arch construction throughout the length thereof in a fashion corresponding to the formation of the loops in the construction shown in the application for Letters Patent above referred to.

The loop converges inwardly from its ends to its mid-length as particularly shown in Fig. 1 thus forming the loop of a width slightly less than the width of the slot 14 formed in the plate on extruding the metal extending between the slits 12 and 13. By thus narrowing the loop it is possible to insert it through a slot having a width corresponding to the width of the slot 14. The protrusion 10 is formed with a central opening 15 for engagement with or by an anchor such as a nail 16.

In the application of the invention, as shown in Figs. 5 and 6, the recess 11 is filled with a plastic material 17, such as tar or asphaltum preferably at the time of applying the hanger to a roof, and

the hanger A is applied to the surface of the water shedding membrane 18 covering the sheathing 19 of the roof structure; the hanger A being arranged to extend longitudinally in the direction of the 5 inclination of the roof.

- 10 The nail 16 is passed through the opening 15 and through the plastic 17 and is driven into the sheathing through the membrane 18 until the head of the nail abuts against the outer face of 15 the protrusion 10 around the margin of the opening 15 and in such manner as to force the upper end portion of the hanger A tightly against the outer surface of the membrane 18, and in some instances partially embed the upper margin of the 20 hanger A in the membrane. In this operation, a portion of the plastic body 17 will be forced outwardly around the margin of the upper portion of the hanger A and also through the opening 15 around the head of the nail 16, thus securely 25 sealing the areas adjacent the nail hole through the membrane 18 against leakage. In some instances the hole 15 may be formed by driving the nail through the protruding wall of the recess 11.

A series of the hangers are thus attached to the 25 roof in suitable spaced relation throughout the area thereof.

In tiling the roof, the arrangement shown in Fig. 5 is preferably employed, that is by laying a row of pan tile 20 on the roof surface with adjacent tiles spaced suitable distances apart and with contiguous pairs of the pan tiles secured by tile supporting wires or ties 21 to the loops 9 of alternate hangers A, and then arranging cover tiles 22 to overlap the adjacent tiles of each pair 30 of pan tiles and connecting the upper ends of such cover tiles by ties 23 to the loops 9 of the hangers A to which the pan tile supporting ties 21 are connected. A cover tile 24 is then positioned to overlap contiguous tiles of adjacent pairs of the pan tiles, 35 and is connected by a supporting tie 25 to the loop 9 of a hanger A interposed between or disposed adjacent the hangers to which pan tiles 20 and cover tiles 22 are connected as shown in Fig. 5.

The ties leading from the hangers and connecting 40 the cover tiles lead on an upward incline from the loops 9 to their points of intersection with the tiles, whereby the weight of the tile effects an upward pull on the lower end of the hanger A tending to rock the latter with the head 45 of the nail 16 as a fulcrum in such fashion as to impart a downward pressure upon the upper end of the hanger A tending to force the latter into snug and tight contact with the membrane 18. This depression of the upper margin of the hanger 50 A insures against the latter being tipped upwardly such as to permit ingress of water beneath the upper end of the hanger, and by this arrangement such bending of the nail 16, as might be occasioned under the load imposed 55 thereon will not interfere with the seal afforded by the upper end of the hanger where it contacts the membrane 18. However, the dome like protrusion 10 is formed to project close to the flat upper face of the hanger A so that when the nail 60 16 is driven in place, the upper or protruding portion of the shank thereof will project but a short distance from the upper face of the sheathing 19, and by use of nails of sufficient strength, little or no bending of the nail will occur, and 65 consequently no enlargement of the perforation made by the nail in the membrane 18 will be apt to take place.

The hanger A is especially applicable for use in affording a connection between intermediate 70 portions of the water shedding roof surface and

tile supporting runners 26 of the type embodying a series of extruded loops 27, as shown in Fig. 7; the hanger A being affixed to the roof as before described, and as shown in Fig. 6, so as to extend longitudinally in alignment with the runner 26 5 and so positioned that the loop 9 will extend through the runner into engagement with a loop 27 of the runner so as to nest therewith from the under side thereof, whereupon wires or pins 28, or other suitable fasteners, are passed through 10 the interconnected loops of the hanger and runner thus effectively tying the hanger to the runner; it being understood that the hangers 26 are ordinarily affixed only at their upper ends under flashing and are not designed to be secured at 15 points in the water shedding surface of a roof.

Manifestly the hanger is applicable for use in affording a means of securing various forms of tile, slabs, and the like and of other forms of runners and the like to roof surfaces, than as here 20 shown, and accordingly we do not limit ourselves to the particular usage here shown, and furthermore we do not restrict ourselves to the exact structure herein set forth but consider that the invention contemplates any structure coming 25 within the meaning of the terms of the accompanying claims.

For example the hanger may be employed in the construction of tile covered concrete roofs which ordinarily are not provided with a surfac- 30 ing membrane. In this instance a nail 39 or similar anchor is imbedded in the body of the concrete 31 with a pointed end protruding upwardly therefrom as shown in Fig. 8. After the concrete has set and in readiness for reception of the tile 35 covering, the hangers A are put in place by applying plastic to the recesses 11 and then inserting the upwardly protruding pointed ends of the nails 39 through the openings 15 whereupon the nails are bent or clinched over the protrusion 10 in such manner as to tightly secure the hanger in place on the concrete slab. In like manner anchors 39 may be imbedded in a hardened concrete roof by drilling holes in the concrete and thereafter cementing the anchor there- 40 in to provide the upwardly extending projections 45 for engagement with the hangers.

Furthermore in some instances the plastic receiving recesses 11 may be dispensed with and the upper end portion of the hanger formed with an opening 10' shown in Fig. 9 as where the hanger is to be nailed to a roof structure in a position where the upper end portion thereof may be covered by flashing or the lower edge of an overlapping layer of membrane 32. In this instance 50 the use of a plastic or cement around the nail hole in the under membrane is not essential since the overlying membrane 32 serves to afford a covering for the nailed upper portion of the hanger in a fashion which will provide a seal for 55 the nail hole. However, in this instance a plastic such as tar may be applied over the nail head previous to the application of the overlying membrane.

We claim:

1. A roofing tile hanger comprising a metallic plate formed with a plastic receiving recess on its under side adjacent one end thereof having an anchor receiving opening in the top wall thereof, and a loop adjacent the other end thereof protruding from the side of said plate opposite said recess and arranged in spaced relation thereto adapted to be engaged by tile engaging ties.
2. A roofing tile hanger comprising a metallic plate formed with a plastic receiving recess on its 70

under side having an anchor receiving opening in the top wall thereof, and a loop adjacent the other end thereof protruding from the side of said plate opposite said recess and arranged in spaced relation thereto adapted to be engaged by tile engaging ties.

5 3. A roofing tile hanger comprising a metallic plate formed with a plastic receiving recess on its under side adjacent one end thereof, and a loop adjacent the other end thereof protruding from the side of said plate opposite said recess and arranged in spaced relation thereto adapted to be engaged by tile engaging ties.

10 4. A roofing tile hanger comprising a metallic plate formed with a plastic receiving recess on its under side adjacent one end thereof having an anchor receiving opening in the top wall thereof, and a loop protruding from the side of said plate opposite said recess and arranged in spaced relation thereto adapted to be engaged by tile engaging ties.

15 5. A roofing tile hanger comprising a metallic plate formed with a plastic receiving recess on its under side and a tile tie receiving loop on its upper side.

20 6. A roofing tile hanger comprising a metallic plate formed with a plastic receiving recess on its under side and a tile tie receiving loop on its upper side, said recess and loop being spaced apart longitudinally of said plate.

25 7. A roofing tile hanger comprising a metallic plate formed with a plastic receiving recess on its under side and a tile tie receiving loop on its upper side, said recess being formed with an anchor receiving opening in the wall thereof.

30 35 8. In a tile roof construction, a membrane covered roof structure, a hanger plate secured to said structure through said membrane, a seal

surrounding the connection between said hanger and roof structure, a loop extruding from said hanger, a tile tie fastened to said loop, and roofing tile supported on said covered roof structure carried by said tie.

5

9. In a tile roof construction, a membrane covered roof structure, a hanger plate secured to said structure through said membrane, a seal surrounding the connection between said hanger and roof structure, a loop extruding from said hanger, 10 a tile supporting runner on said covered roof structure, and a connection between said runner and said loop.

10. In a tile roof construction, a roof structure, a plate of sheet metal extended longitudinally in 15 the direction of the slope of said roof structure, a loop protruding from said plate adjacent the lower end thereof, an opening adjacent the upper end of said plate, means engaging said opening fastening said plate to the roof structure, tiles 20 supported on said roof structure, and ties connecting said tiles to said loops.

11. In a tile roof construction, a membrane covered roof structure, a sheet metal plate extended longitudinally on the surface of said structure, an opening adjacent the upper end of said plate, a nail driven through said opening engaging said roof structure having a head bearing on said plate, tile supported on said roof structure, and 25 a tie connecting said tile to an end portion of said plate leading upwardly from the latter tending to rock said plate with said nail as a fulcrum to force the upper end of said plate downwardly into engagement with the membrane on said roof 30 structure.
